UNITED STATES PATENT OFFICE.

GEORGE RILEY AND HANS E. OLSEN, OF PETALUMA, CALIFORNIA.

AUTOMATIC AUXILIARY AIR CONTROL FOR GAS-ENGINES.

1,097,944.

Specification of Letters Patent. Patented May 26, 1914.

Application filed January 31, 1912. Serial No. 674,597.

To all whom it may concern:

Be it known that we, GEORGE RILEY and HANS E. OLSEN, both citizens of the United States, residing at Petaluma, in the county of Sonoma and State of California, have invented new and useful Improvements in Automatic Auxiliary Air Control for Gas-Engines, of which the following is a specification.

10 This invention relates to an automatic, auxiliary, air controlling appliance for gas engines.

It is the object of this invention to provide an automatic air admission appliance 15 for attachment to the intake of gas engines between the engine and carburetor, by means of which the proportions of air and gas in the explosive mixture delivered to the engine cylinders, will be varied to suit different conditions, such as are occasioned by changes in 20 temperature and altitude, or other causes, thereby maintaining a proper mixture at all times.

Another object is to provide means for admitting air to the engine cylinder on the working stroke of the engine piston, after 25 the throttle valve is closed, to form a cushion for the piston on its return stroke to retard the engine and thereby act as a brake.

30 A further object is to provide a device of the above character which is simple in construction, efficient in operation, inexpensive in manufacture, and not liable to get out of order.

35 Other objects, together with the advantages to be derived from the use of this invention, will appear hereinafter.

The invention consists of the parts and the construction and combination of parts, 40 as hereinafter more fully described and claimed, having reference to the accompanying drawings, in which—

Figure 1 is a view in elevation of a four cylinder gas engine, with parts broken away, 45 showing the invention as applied. Fig. 2 is a vertical section of the invention partly in elevation. Fig. 3 is an elevational view of same. Fig. 4 is a plan view.

In the drawings, A represents a gas engine 50 cylinder of any suitable type and 2 indicates the intake or feed pipe for delivering an explosive mixture of gasoline and air to the interior of the cylinder at the upper end thereof. A carburetor 3 of any desired 55 construction connects with the pipe 2 in the usual well-known manner, through which

the gasoline or other volatile liquid and air is delivered to the pipe 2 from any source of supply. The customary throttle valve 4 is disposed in the pipe 2 between the carburetor 3 and the inlet to the cylinder A, by means of which the quantity of the mixture introduced into the engine cylinder is regulated.

The essence of this invention resides in 65 disposing a peculiarly constructed, auxiliary air-inlet device in the pipe 2 between the throttle valve 4 and the inlet to the cylinder A, which device is designed for the purpose of admitting a quantity of air to the engine cylinder on the charging stroke, to increase 70 the volume of air in the explosive mixture delivered through the carburetor 3 and throttle valve 4; and which is so constructed as to automatically regulate the quantity of 75 air passing therethrough in proportion to the quantity of the explosive mixture passing through the throttle valve 4; and which can be set to vary the proportions as circumstances require.

80 The air inlet valve constituting our present invention is particularly shown in Figs. 2 and 3 of the drawing, and comprises a cylindrical casing 5 tapered inwardly on its outer periphery from its lower to its upper 85 end. A threaded nipple 6 is formed on the lower end of the casing 5 which is adapted to be screwed into the pipe 2, and the upper end of the casing 5 is threaded to receive a cap 7.

A sleeve 9 is slidably mounted on the tapered exterior of the casing 5, with its inner wall conforming to and contacting the outer wall of the casing. The sleeve 9 is formed with an open side or slot 10 and is designed to be rotated a partial revolution by means 95 of a lever arm 11 attached thereto, to expose a series of perforations 12 and a vertically disposed slot 13 formed in the casing 5, as shown in Fig. 3; the lever arm 11 being operated through a connecting rod 14 from 100 any desired point.

An expandable spiral spring 15 is wound around the casing 5 adjacent its upper end, which bears between an overhanging portion of the cap 7 and the upper end of the sleeve 105 9 to normally retain the tapered inner surface of the sleeve in contact with the tapered outer surface of the casing 5, thereby insuring a close fit between the sleeve and casing. The spring 15 thus acts to hold the sleeve 9 110 in its lowermost position and crowds it down on the casing 5, thereby compensating for

wear of the contacting surfaces of the casing 5 and sleeve 9.

Within the casing 5 is a piston 16 which is loosely mounted on a stem 17 extending through and guided in the cap 7. The piston 16 is normally held in its uppermost position in the casing 5 by means of a helical spring 18 wound on the stem 17 and bearing between the upper end of the cap 7 and an adjustable collar 19 threaded on the upper end of the stem 17. A lock nut 20 is screwed on the stem 17 above the collar 19 and is provided for holding the collar 19 against being displaced.

15. The piston 16 is provided as a means for automatically closing the perforations 12 and slot 13 in the casing 5, or portions thereof, to regulate the quantity of air admitted to the interior of the casing 5, as will presently be described. A pin 21 on the casing 5 acts on the vertical edges of the slot 10 to limit the movement of the sleeve 9 in either direction in opening or closing the perforations 12 and the slot 13.

20. In the operation of this invention, when it is desired to increase the quantity of air in the explosive mixture discharged through the carburetor 3 and throttle valve 4, the sleeve 9 is turned to expose a portion of the 30 perforations 12 through the slot 10; the extent of the exposure of the perforations 12 being varied according to the amount of air it is desired to deliver to the explosive mixture. When a small quantity of air is desired, a few of the perforations 12 are opened, and when a large volume of air is required, the sleeve 9 is turned to open all the perforations 12 and the slot 13. The air is drawn into the casing 5 and from 40 thence into the feed pipe 2, where it minglesthe explosive mixture when the throttle valve 4 is open, by the suction of the engine piston on its down stroke, and is drawn into the engine cylinder A with the 45 explosive charge in the usual manner. As most carburetors are improperly set for proper proportions of air and gasolene under varying conditions, the most common of which are changes in altitude and tem-

50 perature, the operations of the engine will vary accordingly. By the use of this invention this difficulty is obviated, for when the engine is operating improperly, the attendant adjusts the sleeve 9 to cause more 55 or less air to be mingled with the explosive mixture as the occasion may require. The quantity of air mingling with the explosive mixture is governed by the open areas of the perforations 12 and the extent of the 60 opening of the throttle valve 4; the latter controlling the speed of the engine. The smaller the open area of the throttle valve 4, the greater will be the suction of the engine piston, thereby increasing the suction 65 in the casing 5 which tends to increase the

volume of air drawn through the perforations 12.

It is desirable that the air passing through the perforations 12 should be proportional to the mixture passing through the throttle valve, and this is accomplished by reason of the piston 16 which operates automatically to close a number of the perforations 12 when the throttle 4 is partially closed; the piston 16 being drawn down by the increased suction in the casing 5 in opposition to the spring 18, the tension of which is adjusted by means of the flange 19 to suit the conditions. When the throttle valve is opened to increase the speed of the engine piston, the suction in the casing 5 becomes less and the piston 16 rises to let in a proportionately larger quantity of air. When the throttle valve 4 is completely closed while the engine is running, a certain quantity of air is drawn into the engine cylinder through the perforations 12 or slot 13 on each down stroke of the engine, and is compressed on the up-stroke. This action retards the engine movements and thereby acts as a brake. In this application of the invention, the sleeve 9 may be turned to open the slot 13, which will permit of a quick inrush of a large volume of air into the engine cylinder.

Having thus described our invention, what we claim and desire to secure by Letters Patent is—

1. An auxiliary air control for an intake pipe of a gas engine comprising a valve 100 adapted to be operated by engine suction, and manual means for varying the amount of air admissible through said auxiliary air control independent of said valve.

2. An auxiliary air control for an intake 105 pipe of a gas engine comprising a valve adapted to be operated by engine suction, and manual means for varying the amount of air admissible through said auxiliary air control independent of the valve, said means 110 including a rotatable sleeve and a connection with the sleeve for operating said sleeve.

3. An automatic air feeding device for gas engines, comprising a valve casing having air inlet openings, means exterior of 115 the casing for opening and closing the openings, and means on the interior of the casing adapted to be operated by suction for closing the openings.

4. An automatic air feeding device for 120 gas engines, comprising a casing having air inlet openings, manually operated means for opening and closing said openings, and suction operated means for closing said openings.

5. An automatic air feeding device for 125 gas engines, comprising a casing having air inlet openings, manually operated means for opening and closing said openings, suction operated means for closing said openings,

- and means for adjusting said suction operated means.
6. An automatic air feeding device for gas engines, comprising a casing having air inlet openings therein, means for attaching said casing to the engine feed pipe, a sleeve formed with a slot revolvably mounted on said casing, means for rotating said sleeve to admit air to the interior of the casing through the perforations in the casing and the slot in the sleeve, and suction operated means inside the casing for closing the perforations.
7. An automatic air feeding device for gas engines, comprising a casing having air inlet openings therein, means for attaching said casing to the engine feed pipe, a sleeve formed with a slot revolvably mounted on said casing, means for rotating said sleeve to admit air to the interior of the casing through the perforations in the casing and the slot in the sleeve, and suction operated means inside the casing for closing the perforations, including a piston, a stem on which the piston is mounted, and adjustable spring means for retracting said piston.
8. An automatic air feeding device for gas engines, comprising a casing having air inlet openings therein, means for attaching said casing to the engine feed pipe, a sleeve
- formed with a slot revolvably mounted on said casing, means for regulating the frictional engagement of the sleeve with the casing, means for limiting the rotary movement of the sleeve, means for rotating said sleeve to admit air to the interior of the casing through the perforations in the casing and the slot in the sleeve, and suction operated means inside the casing for closing the perforations, including a piston, a stem on which the piston is mounted, and adjustable spring means for retracting said piston.
9. In a device of the class described in combination, a casing provided with openings, a revolvable member provided with a slotted portion and adapted to rotate upon said casing, a piston within said casing and adapted to open and close said openings, and a spring tending to resist the movement of said piston to close said openings, substantially as described.
- In testimony whereof we have hereunto set our hands in the presence of two subscribing witnesses.
